UNITED STATES PATENT OFFICE

WARREN W. CECIL, OF DIXON, CALIFORNIA

EGG PACKING MECHANISM

Application filed October 10, 1928. Serial No. 311,456

The invention relates to improvements in egg gathering and packing apparatus together with a relative method of utilizing the same to the end that the factors of economy of handling, economy in cost, and the elimination of breakage in carrying out the method are the paramount factors of employing and practicing the invention.

1 The invention consists of a carrier con-
10 tainer of portable size provided with a main
chamber, constituting the accumulator sec-
tion, one or more auxiliary sections, consti-
tuting the storage sections for the crate sep-
arator flats or fillers, said accumulator sec-
15 tion or main chamber having separably dis-
posed therein a packer mechanism having
associated therewith means for conveying the
eggs disposed in their fillers from such col-
lector means to a shipping crate without re-
20 handling same, or for the operation of trans-
ferring eggs within the compartmented fill-
ers from one shipping case or crate to another,
exclusive of the use of packing chambers, ob-
viating the injury to the hands of the packer,
25 eliminating breakage, and providing substan-
tially a single functioning device to perform
a multiplicity of steps involved in known
methods.

The object of the invention resides in the
30 providing of a light and durable carrier made
of sheet metal, provided with a central pack-
ing compartment that may be carried with
ease during the gathering of eggs, said carrier
being also provided with compartments into
35 which a number of fillers may be placed dur-
ing the gathering of the eggs, and employed
within the packing compartment as needed.
Said packing compartment may have any de-
sired capacity, and when filled is carried to
40 the point of crating, the carrier is then re-
leased therefrom and said packing structure
is depended within such packing case, and the
supporter releasing means is actuated to cause
45 all of the compartmented fillers with eggs in
proper juxtaposition to be deposited within
the shipping crate, without the aid of addi-
tional handling and eliminating entirely any
possible injury to the operators manually
50 actuating the structure.

Another and further object of the inven-

50 Another and further object of the inven-

tion and its use thereof contemplates a simplified method of collecting or gathering and crating eggs for commercial use. In one embodiment the carrier is taken to the source of gathering eggs, and during the time of packing and assorting the eggs, disposed within the compartmented filler means, until the required number are obtained (eliminating in this instance a second handling) thence carried to the shipping source and packed within the crates or containers to receive same by merely a single operation, that of releasing the packing compartment forming structure, to dispose its contents within said crate, likewise eliminating one or more handling of the eggs, obviating entirely breakage at the final point of handling and packing, and removing from the known methods the injury to the hands of the operatives. 55 60 65

In the following, I describe the general embodiment and nature of the invention the features thereof being more particularly defined hereinafter in the claims. 70

In the drawings Fig. 1 is a vertical section view of the egg carrier, showing the packing chamber or compartment provided with a series of fillers and illustrating the relative position of the device during the time the same is employed to collect or gather the eggs at the point or source of supply; Fig. 2 is a plan view of the carrier and the general structure as employed as an egg collector and packing unit, and Fig. 3, is a detail vertical sectional view of one of the corner supports of the packing compartment means, showing the positioning means in its retaining position and illustrating the specific mechanism arranged for actuation to dispose the collected eggs within a part of or all of the reception space of the usual or general type of packing cases employed for egg packing and shopping purposes.

Similar numerals of reference indicate similar parts throughout the several views of the drawings.

In the drawings 1 designates a carrier receptacle of portable size and form having formed therein a main collector compartment 2 and auxiliary compartments or pockets 3 and 4 adapted to receive a quantity of break- 100

down packing fillers of the type commonly employed in the known methods of packing eggs for commercial handling and shipment, together with a handle 5 and holding clips 6 for retaining the carrier stationary as a unit during the moment of withdrawing the packing structure therefrom.

The packing structure comprises a rectangular frame 7 of any suitable material and consists of four tubular posts 8 fastened to said frame 7 arranged to set normally within the collector compartment 2. Each of said posts 8 have mounted therein rods 9 provided at their upper ends with caps 10 between which and the attaching sleeves 11 of frame 7 are disposed expansive springs 12 arranged as the means of controlling the positions of said rods 9 in said tubes 8, said rods 9 having pivotally mounted on their lower ends fingers 13 arranged to form the removable supporting means for the series of flats or compartmented fillers 14 into which the eggs are gathered and shipped. Rods 9 have cut therein one or more notches 15 as may be required, and said sleeves 11 of frame 7 have pivoted therein at 16, pawls 17 engaged by flat springs 18 for holding said pawls 17 in sliding contact with said rods 9 and when all thereof are in their set positions with relation to said rods provide the position of the packing structure during the moment of collecting the eggs and likewise the moment of retaining the collected packed eggs into position for disposing same within the final commercial shipping container or case or crate.

A strap 19 is disposed within compartment 2 and the ends thereof allowed to engage the sides of carrier 1, its object being to provide means adapted to act as additional support across the bottom layer of flats 14 during the moment of depositing the racked eggs within the shipping crate.

The position of the packing structure shown in Figs. 1 and 3 constitutes the position of same during the egg gathering period and when the required number are gathered, said collector structure is withdrawn from carrier 1 and the element as a unit projected within the packing case, pawls 17 actuated to permit springs 12 to thrust rods 9 upwardly carrying therewith fingers 13 and permitting the gathered eggs in compartmented flats 14 to rest within the packing case, thence said packing structure is withdrawn from said case or crate, the fingers 13 reset by thrusting rods 9 downwardly until pawls engage notches 15 to reset all mechanism, thence disposed within compartment 2 of the carrier 1 and the method of gathering the eggs resumed.

By causing the device to function in the manner described hereinabove, it is apparent that several needless handlings of the eggs are eliminated, in fact the only handling of the eggs necessary in carrying out the inven-

tion is the initial one that of collecting the eggs from the nests, and another and material fault found in the packing of eggs for commercial shipment is entirely obviated, that of causing injury to the hands of packers in their slow and costly methods of depositing separate layers of eggs within walls of a shipping crate. Serious results are known in connection with present day methods of packing, one of the most important ones being the barking of skin upon the hands of operators who have been known to require medical attention immediately after completing one or two crates of eggs for commercial shipment.

The invention may be practiced in the manner as set forth or it may be varied in many ways without departing from the general scope of the method and structure as is herein shown, described and claimed.

What is claimed and desired to be secured by Letters Patent of the United States is:

1. An egg packing mechanism comprising a supporting structure consisting of vertically disposed members, a frame connecting said members arranged to form the housing for a series of compartmented fillers carrying a quantity of packed eggs, means disposed in said members for holding said packed compartmented fillers in said housing, and means for releasing said holding means to dispose said packed eggs within a packing case.

2. A device of the character described comprising a supporting structure consisting of vertically disposed retaining members and a frame connecting said member to form a packer mechanism, thrust rods operative in said retaining members, supporting fingers mounted on the lower ends of said rods, springs mounted on said rods engaging said retaining members controlling the relative positions of said supporting fingers, cams pivotally mounted on said frame engaging means on said rods adapted to hold said fingers in their operative and inoperative positions, manually controlled means for setting said fingers into position to support a series of egg packing flats and separators, and means whereby when said packer mechanism is disposed in an egg crate and said cams released said springs return said fingers within said retaining members and deposits said packed unit of eggs within said crate without handling.

3. A device of the character described including an egg packing mechanism consisting of a unit structure composed of corner supporting posts, a series of connecting rods uniting said structure into a supporting frame, thrust rods disposed in said posts, springs engaging said rods and posts, gripping supporting fingers pivotally mounted in the lower ends of said rods and operative within said posts, cams mounted in said

frame adapted to engage stops in said rods for holding said fingers in their projected supporting position to receive a series of separators and compartmented egg flats into
5 which eggs are packed for shipment and means permitting the manual disposition of said packer unit within an egg crate and when said cams are released permit said springs to withdraw said fingers within said
10 posts to deposit said packed eggs within said crate and thereby eliminate the handling of said eggs and the means of compartmenting same.

In testimony whereof, I have signed my
15 name to this specification this 29th day of August 1928.

WARREN W. CECIL.
